UNITED STATES PATENT OFFICE

JOSEPH FAUSSE, OF MELROSE, MASSACHUSETTS, ASSIGNOR TO UNITED SHOE MANUFACTURING CORPORATION, OF PATERSON, NEW JERSEY, A CORPORATION OF NEW JERSEY

SHOE STIFFENER

Application filed December 6, 1928. Serial No. 324,253.

This invention relates to stiffeners for parts of boots and shoes and is herein illustrated as embodied in a stiffener for the toe portion of a boot or shoe upper.

In the manufacture of shoes, it is customary to employ a toe stiffener to aid in imparting the desired shape to the toe portion of the upper of the shoe and in maintaining this desired shape. In the case of plain-toed shoes, which have no toe cap or tip, it is customary to use a so-called "soft box toe stiffener", that is, one without much stiffness or resilience. It is difficult to obtain a satisfactory effect with a stiffener of this type, since if the stiffener is sufficiently soft to produce the desired effect, it is liable not to support the toe portion of the upper satisfactorily during the wear of the shoe. On the other hand, if the stiffener is sufficiently hard and resilient to hold up the toe portion of the upper of the shoe, it is liable to be so stiff that, after a short period of wear of the shoe, a ridge or break will appear across the toe portion of the upper in register with the rear edge of the stiffener.

It is desirable that the stiffener in the finished shoe should have comparatively stiff front and side portions and a much softer upper portion, since a box toe with such a construction will retain its shape and at the same time will not tend to facilitate the formation of ridges or creases across the toe portion of the upper during the wear of the shoe.

According to the present invention there is provided a stiffener comprising a flexible base, the margin along a selected portion of which carries a stiffening substance. The illustrated stiffener blank comprises a base of sheet material, which has the degree of resilience desired for the upper portion of a soft box toe, the margin along the front and side edges of said blank being treated with a stiffening substance capable of being softened. In the manufacture of a shoe, the stiffening substance is rendered temporarily soft; and, while the substance is in that condition, the blank is incorporated in the upper of the shoe and is conformed to the toe portion of the last. As soon as the stiffening substance has hardened there results a box toe stiffener hav-

ing stiff front and side walls and a comparatively soft upper portion. The particular stiffener, which is illustrated, comprises a base of suitable fabric having a band of thermoplastic substance, such as a mixture of 55 colophony and asphalt, along its front and side margins.

Referring to the accompanying drawings, Fig. 1 is a plan view of a stiffener in which the present invention is embodied; and

Fig. 2 is a sectional view of the stiffener upon the line 2—2 of Fig. 1.

The illustrated stiffener is of the type which is normally flat and consists of a base 3 of flexible sheet material, such as a suitable fabric, which has been skived in the usual manner and carries along its forward margin a stiffening substance. Any suitable stiffening substance may be used which is normally hard and resilient but may be rendered temporarily soft, for example by heat or by a solvent, so that the stiffener may be conformed with the upper to the toe portion of the last. In the illustrated stiffener, the stiffening substance 5 is a thermoplastic one such, 70

for example, as a mixture of 75 per cent colophony and 25 per cent asphalt, said mixture being capable of being softened by a degree of heat which is not injurious to leather; and both sides of the selected margin of the 80 base are coated with this mixture so as to anchor the stiffener firmly both to the lining (including the doubler) and to the upper. Preferably the stiffening substance is so applied, as shown in Fig. 1 of the drawings, that 85 the bands of the stiffening substance are of a given width along the front of the stiffener, and decrease in width as they extend toward the rear of the stiffener. These bands are thus substantially crescent-shaped with 90 the tips of the crescents pointing toward the rear of the stiffener.

The flexible base 3 may be of any material which has the resilience desired for the upper portion of a soft box toe or will have such 95 resilience when incorporated in the finished shoe. For example, it may contain a small amount of stiffening substance like the substance which is carried by the margin or it may contain none at all. In any event, the 100

body portion of the stiffener will contain very much less stiffening substance per unit volume than does the margin along the front and sides. In the illustrated stiffener, the 5 base 3 consists of a rubberized fabric containing no thermoplastic stiffening substance, the fabric being so chosen and the amount of rubber so proportioned that the base has the degree of resilience suitable for the upper portion of a soft box toe in a finished shoe.

10 In the manufacture of a shoe, the stiffening substance of the blank is softened either before or after the blank is incorporated in the upper of a shoe; and the blank is conformed with the upper to the toe portion of the last while the blank is in softened condition. After the stiffening substance has hardened, there results in the finished shoe, as has been indicated, a stiffener having a 15 soft upper portion and comparatively stiff front and side portions. The upper portion of the stiffener, owing to the fact that it is convexly curved and is supported by the comparatively stiff front and sides, offers a firm 20 and at the same time flexible support for the upper part of the toe portion of the upper. Such a stiffener will support the toe portion of the upper of a shoe in a satisfactory manner without either breaking down or causing 25 a ridge to appear across the toe portion.

30 The stiffener of the present invention has been described above as being adapted for use in the method of manufacture of boots and shoes in which the toe portion of the upper is conformed to the last during the pulling-over and lasting operations. It should be pointed out, however, that the stiffener is also well adapted for use in the method of manufacturing boots and shoes wherein the 35 toe portion of the upper is molded to shape before the upper is placed upon the last. In the manufacture of boots and shoes by this method, it is impossible or impracticable to use a soft toe stiffener of the type hitherto 40 known, since, when the toe portion of an upper containing such a stiffener is molded, the toe portion will not retain its molded shape. With the stiffener herein described, however, there is sufficient stiffening substance present 45 in the proper locality so that, after the toe portion of the upper has been subjected to the action of heated molds and then removed from the molds, the stiffening substance 50 hardens and causes the toe portion of the upper to retain the shape which has been imparted to it.

55 Although, for the purposes of explanation, a toe stiffener has been illustrated and described, it should be understood that the invention is not limited in the scope of its application to this particular kind of a stiffener.

60 Having thus described my invention, what I claim as new and desire to secure by Letters Patent of the United States is:

65 1. A stiffener blank for boots and shoes

comprising a base of flexible sheet material, the margin along one edge of the base carrying a stiffening substance, the remaining portion of the blank being soft and flexible.

2. A substantially flat toe stiffener blank 70 adapted to be incorporated in the upper of a shoe, said blank comprising a base of sheet material having, along that margin which in the finished shoe will be adjacent to the sole, a stiffening substance which may be rendered temporarily soft by suitable treatment to permit the blank after it has been assembled with the upper of a shoe to be lasted therewith, but will become hard and resilient in the finished shoe, the remaining portion of the blank 75 being of a flexible material which is substantially unaffected by said treatment.

3. A substantially flat box toe blank having its margin along the front and sides thereof treated with a stiffening substance 80 which is normally hard and resilient but may be rendered temporarily soft and plastic by a degree of heat which is not injurious to leather, the remaining portion of the blank 85 being substantially free from stiffening substance.

4. A box toe blank comprising a base of rubberized material having a thermoplastic substance along the margin at the front and sides thereof, the remaining portion of the 90 blank being substantially free from said substance.

5. A box toe blank the middle and rear portions of the margin of which are composed entirely of flexible sheet material, the margin along the front and sides thereof carrying a crescent-shaped load of stiffening substance adapted to be rendered pliable by treatment with a suitable softening agent.

6. A box toe blank comprising a base of 105 absorbent material having along the margin at the front and sides a load of stiffening substance adapted to be softened by treatment with a given softening agent, the remainder of the blank being flexible and unresponsive 110 to the action of said agent.

In testimony whereof I have signed my name to this specification.

JOSEPH FAUSSE.
